UNITED STATES PATENT OFFICE.

WILLIAM F. HOWARD, OF PIPESTONE, MINNESOTA.

COMBINATION-TOOL.

No. 920,746.

Specification of Letters Patent.

Patented May 4, 1909.

Application filed May 7, 1908. Serial No. 431,390.

To all whom it may concern:

Be it known that I, WILLIAM F. HOWARD, a citizen of the United States, residing at Pipestone, in the county of Pipestone and 5 State of Minnesota, have invented certain new and useful Improvements in Combination-Tools; and I do declare the following to be a full, clear, and exact description of the invention, such as will enable others skilled 10 in the art to which it appertains to make and use the same.

This invention relates to an improved combination tool especially adapted for use in the construction and the repair of wire 15 fences.

The object of the invention is to provide a simply constructed inexpensive and efficient tool of this character which shall combine a wire cutter and staple puller, a hammer, a 20 wire splicer of ordinary construction and a splicer arranged between the parts.

For these and still other objects which will appear as the description proceeds the invention consists of certain novel features, arrangements and combinations of parts of 25 which the herein described combination tool is one of many possible embodiments.

While herein the description refers to minute details of the invention, the invention is 30 not limited to these as the details of construction and combination may be greatly varied without departing from the spirit and scope of the invention.

In the annexed drawing forming a part of 35 this specification in which like reference characters refer to like parts throughout the several views and which are for illustrative purposes only and therefore not drawn to any particular scale,—Figure 1 represents a top 40 plan view of this improved tool; Fig. 2 is a side elevation thereof with the jaws shown in closed position; Fig. 3 is a perspective view of one of the members or jaws detached and with the handle broken off; Fig. 4 is a similar 45 view of the other jaw carrying member; Fig. 5 is a detail perspective view of the pivot member.

In the embodiment illustrated, the jaw carrying member 1 is provided at one end 50 with a staple puller 2 the other end being extended to form a handle 3. This member 1 is provided near its staple puller end with a curved recess 4 to receive the other jaw carrying member hereinafter described.

55 A wire cutting blade 5 is carried by the member 1 and is preferably provided with a

notch 6 for the reception of the wire to be cut, the edges formed by said notch being preferably sharpened to more readily sever the wire. A round aperture 7 extends transversely through the jaw member 1 and is adapted to receive the pivot which connects the jaws. A hammer member 8 is also provided at one side of said jaw member 1 for driving staples and for other purposes. One 60 jaw 9 of a wire splicer is fixed to the member 1 being preferably made integral therewith as shown and has a straight clamping edge 9' adapted for coöperation with another clamping member to be described. 70

A member 10 designed for coöperation with the member 1 is formed with a head 11 which is shaped to fit in the recess 4 of the member 1 and turn therein. A cutting blade 12 is formed on the head 11 and adapted to coöperate with the notch 6, having the sharpened edges for severing a wire, when one of the jaw carrying members is moved relatively to the other. An angular opening 13 is formed in the head 11 and is adapted to 80 register with the opening 7 in the member 1. This opening 13 is shown square to receive the square portion of the pivot member, to be described. The handle members of the members 1 and 10 are preferably provided 85 in the meeting faces thereof, at points near their pivotal connection, with the registering grooves 14 and 15 which are adapted to receive and partially embrace and hold two wires of a fence while making a splice. A 90 pivot member 16 is shown for connecting the members 1 and 10 and is provided with a square portion 17 at one end adapted to fit in the square opening 13 of the member 1 to provide for the turning of said member 16 95 with the member 10. The outer end 18 of the member 16 is made round to fit in the round aperture 7 of the jaw carrying member 1 and on which said members are adapted to pivot. An arm 19 extends laterally 100 from the square end 17 of the pivot member 16 to form the movable member or jaw adapted for coöperation with the fixed splicing member 9 whereby the ends of the wire to be spliced may be securely fastened together by the clamping action produced 105 thereon by the jaws 19 and 9'. 100

I claim as my invention:

1. A combination tool comprising two members adapted for pivotal connection, a 110 fixed splicing jaw carried by one of said members and a pivot member for connecting

said first mentioned members and having a splicing jaw for coöperation with said fixed splicing jaw.

2. A combination tool comprising two members adapted for pivotal connection, one of said members having a head provided with a curved recess therein and having a round aperture extending transversely through the end wall of said recess at the center thereof, the other member having a curved head to fit in said recess and having an angular aperture to register with the round aperture in the other member, a fixed splicing jaw carried by the member having

the recess therein and a pivot member having 15 an angular portion for engagement with said angular aperture and having its outer end rounded to fit in the round aperture of the other member and a splicing jaw carried by said pivot member for coöperation with said 20 fixed splicing jaw.

In testimony whereof I have hereunto set my hand in presence of two subscribing witnesses.

WILLIAM F. HOWARD.
